(57) **CLAIM**

I claim the ornamental design for display screen or portion thereof with graphical user interface for recipe visualization, as shown and described.

DESCRIPTION

The sole FIGURE is a front view of a display screen or portion thereof with graphical user interface for recipe visualization.

The outermost broken lines in the drawing illustrate a display screen or portion thereof, and form no part of the claimed design. The remaining broken lines in the drawings illustrate portions of the graphical user interface and form no part of the claimed design.
